Primary Examiner — Holly H Bayham(74) *Attorney, Agent, or Firm* — Stetina Brunda Garred & Brucker(57) **CLAIM**

The ornamental design for a drawer slide auto-close dampening mechanism, as shown and described.

DESCRIPTION

FIG. 1 is a front perspective view of the drawer slide auto-close dampening mechanism of the present invention showing our new design with the dotted lines depicting solely environmental structure and forming no part of the claimed design;

FIG. 2 is a rear perspective view thereof;

FIG. 3 is a top plan view thereof;

FIG. 4 is a left end view thereof;

FIG. 5 is a side elevational view thereof;

FIG. 6 is a front end view thereof;

FIG. 7 is a bottom plan view thereof; and,

FIG. 8 is a rear elevational view thereof.
